UNITED STATES PATENT OFFICE.

JAMES KENNEDY, OF KINGSTON, JAMAICA, WEST INDIES.

FIBER-MACHINE.

SPECIFICATION forming part of Letters Patent No. 350,063, dated September 28, 1886.

Application filed January 30, 1886. Serial No. 190,301. (No model.)

To all whom it may concern:

Be it known that I, JAMES KENNEDY, of 5 Kingston, Jamaica, West Indies, have invented a new and Improved Fiber-Machine, of which the following is a full, clear, and exact description.

This invention relates particularly to machines for treating the leaves, stalks, and other portions of fiber-bearing plants for obtaining 10 fiber therefrom (after partial setting to soften the skin or rind adhering to the pulp) without chemical treatment.

The improvement consists, principally, in the shape and position of the scraping-block, 15 it being placed directly above the series of revolving scrapers, and the face of the block being a flat surface instead of a concave surface, as heretofore.

The invention also consists in constructing 20 the scraping-block in such manner that the feeding may take place from the side of the machine and permit the stalks, leaves, &c., to be drawn outward, thereby making a positive feed, whereas in the present machines the 25 fiber, &c., must be introduced into the machine at the same side at which it is withdrawn.

The invention also consists in supporting 30 the scraping-block by springs arranged to prevent recoil and vibrating action, which is detrimental to a nice adjustment of the block and rapid action.

The invention finally consists of the construction, arrangement, and combination of 35 parts, all as hereinafter described and claimed.

Reference is to be had to the accompanying 40 drawings, forming part of this specification, in which similar letters of reference indicate corresponding parts in both the figures.

Figure 1 is a side elevation of my new and 45 improved fiber-machine, and Fig. 2 is a transverse sectional elevation taken on the line xx of Fig. 1.

A represents the frame of the machine, in which the main shaft B is journaled, and which 50 supports the table C and the overhanging arm D. Upon the shaft B is secured the macerating-drum E, that carries the rollers E' and radial scrapers E''. The overhanging arm D supports the scraper-block F, between which and the scrapers and rollers E' E'' the fiber material is treated. The block F is rectangu-

lar in shape, and is formed with the flat surface a and rounded corners a' a'' , and at its outer end it is beveled off, as shown at a^2 , to facilitate the feeding of the material to be treated to the machine. The block F is, by preference, held in a metal frame, G, which is attached to the lower ends of the upright screw- 55 rods H H, held loosely in openings in the overhanging arm D. Upon the screw-rods H are placed the coiled springs I I, which act between the upper flange, d , of the arm D and the nuts b on the rods H, and consequently press the block F downward, but permit it to yield in case any uneven or large mass of material should enter the machine. Upon the upper ends of the screw-rods H are placed the nuts J, by which the block may be raised or lowered. By turning the nuts b up or down upon the screw-rods I the tension of the springs 60 65 I may be increased or diminished, as desired, and by adjusting these nuts the pressure may be accurately regulated to the material to be treated, so that there will be no recoil and vibrating action of the springs, which is always 70 detrimental to good results. Rising from the table C are the pins or studs K K', for the purposes described below.

In operating the machine one person places the leaf or stalk to be treated upon the table 80 C alongside the stud K, with its butt-end toward the block F. Another person now reaches over from the opposite side of the table and takes the butt-end of the leaf and enters the same sidewise into the opening marked W 85 until the plant reaches the stud K', and now the leaf or stalk is drawn outward against the stud K' as a guide in the oblique direction to the center of the shaft B and from the right hand to the left until the fiber is completely 90 withdrawn beyond the stud K', which acts to keep the fiber over the center of the scrapers E''. The rapid rate at which the scrapers revolve tends to keep the fibers in straight lines, thereby preventing the entanglement and 95 waste so common with other fiber-machines, as the fibers are constantly subjected to tension. By constructing the scraper-block F straight and flat upon its lower surface, a , it is an easy matter to adjust it to the scrapers, 100 and the arrangement of the springs and nuts on the rods that support the scraper-block

affords a ready means of adjusting the block F, and prevents the block from going too near the scrapers while the plant is being cleaned, and the studs K K' cause the fiber to pass directly 5 over the top of the scrapers, thereby removing all the pulp. The beveling of the outer end of the block A and the arrangement of the machine whereby the material to be treated can be introduced at the side of the machine 10 instead of pushing it in endwise and then withdrawing it (as it is now performed) cause the action of cleaning to be most perfectly done while the leaf is being withdrawn.

Another advantage arising from the arrangement of this new machine is, that the leaf is 15 always under tension, which removes the difficulty heretofore experienced—viz., that of pushing in a limp, softened plant.

Having thus described my invention, what 20 I claim as new, and desire to secure by Letters Patent, is—

1. In a fiber-machine, the block F, held above the table and macerating-drum and formed with a flat lower surface, a, substantially as 25 described.

2. In a fiber-machine, the block F, held in

the overhanging arm D by the adjustable rods H, having the springs I placed therein, substantially as and for the purposes set forth.

3. The table C, provided with guide pins or 30 studs, in combination with the block F and macerating-drum E, substantially as described.

4. In a fiber-machine, the table C and macerating-drum E, in combination with the overhanging arm D, supporting the block F, where- 35 by the material may be fed into the machine at the end of the block F, substantially as de- scribed.

5. The scraper-block F, made flat upon the bottom and beveled at a², substantially as and 40 for the purposes set forth.

6. The block F, held in the frame G, in com- bination with the screw-bolts H, overhanging arm D, springs I, and nuts b J, for adjusting the block and the tension of the springs, sub- 45 stantially as described.

JAMES KENNEDY.
